UNITED STATES PATENT OFFICE.

WILLIAM H. BAKER, OF CHEROKEE, OKLAHOMA.

DOSER.

1,266,383.

Specification of Letters Patent. Patented May 14, 1918.

Application filed September 11, 1917. Serial No. 190,779.

To all whom it may concern:

Be it known that I, WILLIAM H. BAKER, a citizen of the United States, and a resident of Cherokee, in the county of Alfalfa and State of Oklahoma, have made certain new and useful Improvements in Dosers, of which the following is a specification.

My invention relates to devices for administering medicine in a liquid form and more particularly to instruments for dosing hogs, and has for its object to provide a device whereby a hog can easily be handled and the medicine easily and more certainly applied internally.

With this and other objects in view my invention consists in certain novel features of construction, arrangement and combination of parts, reference being had to the accompanying drawing in which—

Figure 1 is a perspective view showing the use of my invention.

Fig. 2 is a side elevation of the same.

Fig. 3 is a bottom plan view with central tube in section.

In carrying out my invention I use a tong like structure consisting of a straight bar member 10 having an enlargement 11 with a central opening 11^a and rounded extension 12 connected to the enlargement 11 by the flattened portion 13 which is provided with an opening to receive one end of a chain as will be hereinafter further set forth. Pivoted to member 10 at 10^a is a jaw clamping member 13^c the handle portion 13^a of which is straight and extends alongside of the handle 10 as shown in Fig. 3. To the upper end of the bolt or rivet 10^c one end of a chain 14 is secured, the upper end being secured at the side of a funnel member 15, while a similar chain 14^a is secured to the opposite side of the funnel and its lower end being secured in the eye 13^b, in the flattened portion 13 of the member 10 as before pointed out.

Passing through the central opening 11^a in the enlargement 11 is a flexible tube 16 having a metal thimble 16^a on its lower end so that the end of the tube 16 may not be withdrawn through such central opening. The funnel is secured to the upper end of the flexible tube which may be a rubber hose.

As stated the device is for dosing or administering medicine to hogs, and to use same the hog which is to be treated is

placed on its back as shown, the person holding the hog standing astride of the hog, and holding both front feet; the straight bar through which the rubber tube passes is then placed in the hog's mouth as far back as possible acting as a guide and also as a spreader and prevents the hog from closing its mouth. The curved bar or member 13 is then clamped down on the hog's lower jaw which keeps it from shaking its head; the rubber tube 16 is then run down the throat of the hog for the required distance and the medicine poured into the funnel 15 at the outer end of the tube 16 until the desired dose is given. When this has been done the tube is withdrawn from the hog's throat and as soon as the tube leaves the throat the hog will swallow. The chains 14 and 14^a are used to keep the hose and speculum or guide together and to prevent the tube from being completely removed from the hog's throat before the speculum is removed from the hog's mouth.

It will thus be seen that I provide a simple and efficient device for readily administering medicine to a hog which has heretofore been a difficult and unsatisfactory treatment.

I claim:

1. In a device of the character specified, a jaw spreader member to be inserted within the mouth of an animal, a lower-jaw clamping member movably connected therewith, a flexible tubular member to receive medicine and carried by said jaw spreader member, and flexible means connecting said tubular member with the jaw spreader and jaw clamping members.

2. In a device of the character specified, a jaw spreader member comprising a handle an enlarged intermediate portion having a central opening and an extension having an eye therein, a jaw clamping member pivotally connected with the jaw spreader member and having a handle and a curved jaw gripping arm adapted to act in conjunction with the enlargement of the jaw spreader member to complete the gripping action, a flexible tubing slidably held in the central opening of the jaw spreader member, a funnel means at one end of the tubing for filling same with a medicine, and means at its opposite end to prevent its withdrawal from

the mouth portion of the jaw spreader, and flexible means connecting the upper portion of the tubing with the jaw spreader member.

3. A device of the character specified and consisting of a tongs like structure including a member for insertion in the mouth of an animal and spreading the jaws thereof, said

member having an opening therethrough, a flexible hose slidably mounted in said opening, a funnel at one end of said hose, and 10 flexible means connecting the funnel with the jaw spreading member at each side of the hose.

WILLIAM H. BAKER.
